UNITED STATES PATENT OFFICE.

JOHN P. NEFF, OF EAST ORANGE, NEW JERSEY, ASSIGNOR, BY MESNE ASSIGNMENTS, TO AMERICAN ARCH COMPANY, OF NEW YORK, N. Y., A CORPORATION OF DELAWARE.

OIL-BURNING LOCOMOTIVE.

1,138,064.

Specification of Letters Patent.

Patented May 4, 1915.

Original application filed October 1, 1913, Serial No. 792,782. Divided and this application filed October 26, 1914. Serial No. 868,652.

To all whom it may concern:

Be it known that I, JOHN P. NEFF, a citizen of the United States, and a resident of East Orange, county of Essex, and State of

5 New Jersey, have invented certain new and useful Improvements in Oil-Burning Locomotives, of which the following is a specification.

10 My invention relates to improvements in locomotives and has particular reference to improvements in the fire boxes of locomotive boilers.

15 This application is a division of my pending application, Serial No. 792,782, filed October 1, 1913.

The object of my invention is to provide 20 an oil-burning furnace for locomotives in which the several parts of the refractory lining shall be positively held in position; in which parts of the fire box lining shall mutually aid in retaining each other in position; in which it shall be easy to replace a burned-out brick by a new one, and in which parts of the lining shall be easily removable 25 for inspection or repair of the lower edge or mud-ring of the fire box.

A further object of my invention is to 30 provide a furnace for oil-burning locomotives in which the thickness of refractory lining shall be proportioned, in the different parts thereof, to the severity of the action of the heat thereon, and in which the mud-ring rivets shall be protected against the direct action of the high temperatures in the furnace without adding materially to the 35 weight of the lining.

A further object of my invention is to 40 provide a pan construction and a refractory lining for oil-burning locomotives by which the lower edge of the furnace, or, in other words, the mud ring, shall be effectually protected from the direct action of the heat of combustion; and to provide a lining wherein the shelf bricks can be readily removed to 45 permit examination of the mud-ring rivets without disturbing other parts of the lining.

50 My invention resides in a furnace for oil-burning locomotives in which the shelf bricks are positively held in position and in which they interlock with other bricks of the lining.

My invention also resides in a construction for the lower part of a furnace, for an oil-burning locomotive, which comprises a sheet

metal pan secured to and carried by the firebox walls, and a refractory lining having shelf bricks positively held in position on the shelf. 55

My invention also consists in the several arrangements of parts, and in the features 60 of construction, whereby the above and other objects are attained and all as hereinafter described and particularly pointed out in the appended claims.

My invention will be more readily understood 65 by reference to the accompanying drawings forming part of this specification, and in which:

Figure 1 is a central, longitudinal, vertical section of a locomotive boiler firebox 70 equipped with an oil burner and embodying my invention; and Fig. 2 is a transverse section of the fire box on the line 2—2 of Fig. 1.

In the equipment of locomotive boilers 75 for the use of oil as fuel, it has been the object of inventors for some time to simplify the construction of the pan and its lining, and it is my particular object to provide such a construction wherein the several bricks of the lining shall mutually retain 80 each other in position and wherein the refractory lining can be readily and easily replaced or repaired, and which when once in position, shall be substantially permanent. It has been my object to include in such 85 structure the protection of the lower edge of the fire box, particularly the mud-ring, or in other words, the rivets by which the mud-ring is secured.

A fire-box A, as illustrated in the drawings, is made up of a flue sheet a' , a rear sheet a^2 , a crown sheet a^3 and side sheets a^4 . The fire box itself is joined to the shell of the boiler by means of a mud-ring a^5 , which fills the space between the lower edge of the fire box and the lower edge of the outer shell a^6 of the boiler, forming the lower end of the water leg of the boiler. This mud ring is secured in position between the lower edges of the various sheets by means of 100 rivets a^7 . In the form of my invention illustrated in the drawings the fire box is closed by a sheet iron structure B forming a pan. Its outer edges are connected or secured to the mud-ring by cap bolts b' or some similar 105 devices. The central portion of this sheet iron structure is considerably depressed below the lower edge of the fire box forming a

combustion chamber b^2 , which is somewhat longer than it is wide. The rear end b^3 of this combustion chamber is vertical and is closed. The forward end b^4 is also vertical, 5 and is provided with a centrally arranged opening b^5 in which is placed or held a fuel burner b^6 by which fuel oil is forced into the combustion chamber and against the rear wall b^3 . The side walls b^7 of the combustion chamber are connected at their 10 upper edges to the inner edges of a shelf-like portion b^8 of the pan B. This shelf extends completely around the depressed, central portion and forms what may be termed the 15 main floor of the fire box. In order to preserve the sheet metal structure, forming the pan, from destruction I completely cover it with a lining C of refractory material, preferably in the form of fire brick. I arrange bricks c' against the upwardly and outwardly inclined sides and against the 20 ends of the depressed portion which are of such a length that their lower ends rest upon the floor b^8 , and their upper ends extend 25 slightly above the shelf b^9 . I hold the lower ends of these bricks in position by means of floor bricks c^2 , which rest upon and protect the floor b^8 . I protect the shelf b^9 by means 30 of shelf bricks c^3 , which extend from the side sheets of the fire box and project over the upper ends of the bricks c' . To hold these shelf bricks in position I provide upwardly extending projections b^{10} on the shelf portions of the pan, and which in the 35 form shown are formed by angle irons secured to the floor b^9 , and I provide the shelf bricks c^3 with openings or grooves c^4 in their undersides to receive these projections, said openings c^4 providing the bricks with shoulders c^5 , which engage the projections and hold the bricks c^3 in position against the side sheets of the fire box. The outer ends of the undersides of these shelf bricks are cut away, 40 as shown at c^6 , for the purpose of overlapping the heads of the rivets a' , and thus protecting these rivets, or, in other words, the mud-ring of the fire box against the high temperatures of the fire box gases. As a further means of holding the several bricks 45 in position I make the grooves c^4 wide enough to receive the upwardly projecting ends c^7 of the side bricks c' thus effectively interlocking the shelf bricks and the side bricks and causing them to mutually retain 50 each other in position. Furthermore, the angle iron abutment b^{10} is sometimes de-

stroyed in the operation of the locomotive and even under such conditions the bricks with which the lining is repaired are securely retained in position by this interlocking of the side and shelf bricks. In fact, I sometimes do away with the metallic projection b^{10} depending entirely upon the interlockment of the shelf and side bricks to retain the shelf bricks in position upon the shelf and to prevent the displacement of the side bricks.

I claim:

1. In a locomotive fire box a bottom closing pan having a depressed central portion 70 surrounded by a marginal substantially horizontal shelf, refractory bricks lining the bottom and sides of the depressed portion, and refractory bricks covering said shelf, said shelf bricks being provided with 75 grooves in their lower sides, rigid projections on the shelf entering said grooves and said side bricks having projections rising above said shelf and entering said grooves, as and for the purpose specified.

2. In a locomotive fire box a bottom closing pan having a depressed central portion and a horizontal shelf joining the edges of the depressed portion to the fire box, an upstanding rib on the inner edge of the shelf, refractory bricks lining the bottom and sides of the depressed portion and refractory bricks protecting the shelf, the inner ends of the shelf bricks having grooves receiving both said ribs and the upper ends of said 90 side bricks, as and for the purpose specified.

3. In a locomotive fire box a bottom closing pan having a depressed central portion surrounded by a marginal substantially horizontal shelf, refractory bricks lining 95 the bottom and sides of the depressed portion, and refractory bricks covering said shelf, an upstanding metallic rib extending along the inner edge of the shelf, said side bricks having projections rising above said shelf and said shelf bricks having grooves in their lower sides to receive said ribs and said projections, as and for the purpose specified.

In testimony whereof I have hereunto set 105 my hand this 6th day of October, 1914, in the presence of two subscribing witnesses.

JOHN P. NEFF.
